United States Patent Office

Des. 186,700

Patented Nov. 17, 1959

186,700

COMBINED CALENDAR AND DESK SET BASE

Jacob S. Sherman, Chicago, Ill., assignor to Park Sherman Company, Chicago, Ill., a corporation of Illinois

Application March 3, 1958, Serial No. 49,882

Term of patent 14 years

(Cl. D74—1)

Fig. 1.

Fig. 2

Fig. 3.

Fig. 4.

Fig. 5.

Fig. 1 is a top plan view of a combined calendar and desk set base embodying the design of the present invention;

Fig. 2 is a side elevational view of one side thereof;

Fig. 3 is a side elevational view of the opposite side thereof;

Fig. 4 is a front elevational view thereof; and

Fig. 5 is a rear elevational view thereof.

I claim:

The ornamental design for a combined calendar and desk set base, as shown.
